United States Patent Office

Des. 209,018
Patented Oct. 24, 1967

209,018

BOTTLE

Morris L. Holtz, 17 Holly Drive, Short Hills, N.J. 07078

Filed Dec. 7, 1966, Ser. No. 4,965

Term of patent 14 years

(Cl. D58—6)

FIG. 3

FIG. 2

FIG. 1

FIG. 6

FIG. 5

FIG. 4

The dominant features of my design reside in those portions shown in full lines.

I claim:

The ornamental design for a bottle, as shown and described.
